UNITED STATES PATENT OFFICE.

HERBERT VANDERBEEK, OF CANTON, OHIO, ASSIGNOR TO THE TIMKEN ROLLER BEARING COMPANY, OF CANTON, OHIO, A CORPORATION OF OHIO.

GRINDING MACHINE AND PROCESS.

Application filed June 2, 1923. Serial No. 642,978.

To all whom it may concern:

Be it known that I, HERBERT VANDERBEEK, a citizen of the United States, and a resident of the city of Canton, in the county of Stark and State of Ohio, have invented a new and useful Improvement in Grinding Machines and Processes, of which the following is a specification.

My invention relates to grinding machines and processes, and has for its principal object to devise a machine and process by which conical rollers for roller bearings or like objects may be ground so that they will be of accurately circular section throughout their length. The invention consists principally in pivotally mounting a grinding wheel so that when the grinding wheel is swung about its pivot it has a substantially tangential movement with respect to the roller being ground, and so that the center line of the roller, the center line of the grinding wheel and the point of contact are in a straight line at the completion of the grinding and the translatory movement of the grinding wheel continues until the center thereof is carried past said line. The invention further consists in the process and in the machine, parts and combinations of parts hereinafter described and claimed.

In the accompanying drawing,

Fig. 1 is a front elevation of a grinding machine embodying my invention; and

Fig. 2 is a side elevation thereof.

Rotatably mounted in suitable bearings 1 on the frame 2 of a grinding machine or the like are driving chucks or spindles 3 between which is held the article to be ground. In the drawing, this article is a conical roller 4 for use in roller bearings. In the drawing is shown a preferred form of drive for the spindles 3 in which each spindle is provided with a pulley 5 that is driven by a suitable belt 6. Secured to the frame 2 of the grinding machine adjacent to the spindle pulleys are brackets 7. To each of the brackets 7 are secured pulleys 8 over which passes the belt 6 that drives the spindle. The direction of the drive is indicated by the arrows in Fig. 2. The arrangement shown in the drawing results in the belt exerting a downward pull on the spindles, the pull being in the general direction of the resultant of the forces acting on the roller as it is being ground.

Mounted on the frame of the machine so as to be adjustable toward and away from the work holding spindles 3 is a slide 9. A suitable handle 10 is provided for moving this slide to the desired position. The slide 9 preferably has a bifurcated upper portion 11 and an arm 12 is pivotally secured between the parts of the slide. Rotatably mounted at the outer end of said arm 12 is a grinding wheel 13. The grinding wheel 13 is provided with a suitable pulley 14 over which passes the driving belt therefor. The end of the arm 12 opposite the grinding wheel 13 is preferably provided with projections 16 to each of which is secured a pulley wheel 17 over which passes the drive belt for the grinding wheel. The purpose of this arrangement is to exert a horizontal pull on the grinding wheel that tends to pull it away from the work.

Mounted for cooperation with a suitable member on the grinding wheel or supporting arm is a cam 18 by which the grinding wheel may be raised. The cam 18 shown in the drawings is provided with suitable means for rotating it. The arm 12 on which the grinding wheel 13 is mounted rests on said cam, and as the cam rotates, it swings the arm 12 upwardly about its pivot. After the arm 12 has been raised, the continued turning of the cam 18 permits the arm and grinding wheel to lower by their own weight. When a roller is in position to be ground, the grinding wheel is raised. As the grinding wheel lowers through its arcuate path, it comes in contact with the roller and grinds it. The mechanism is so arranged that the roller is ground to the proper size when the center lines of the roller and of the grinding wheel and the point of contact between the roller and grinding wheel are in a straight line. Preferably the axis about which the arm 12 swings is in the same line. As the grinding wheel continues to lower, it gradually ceases to grind the roller. By this arrangement, the grinding wheel at first grinds deeply but it grinds less and less until the work is completed. It moves gradually away from the roller, instead of stopping work abruptly, thus avoiding the formation of rough spots or ridges on the roller and insuring that the rollers shall be of accurately circular section throughout their length. In the drawing, the grinding wheel

is shown grinding conical rollers. The grinding wheel may be adjusted for rollers of different degrees of taper or for cylindrical rollers. Preferably the axes of the 6 grinding wheel and of the roller being ground are parallel and the face of the grinding wheel is inclined with respect to its axis, so that said face conforms to the taper of the roller. Different tapers may 10 be taken care of by using grinding wheels whose faces make different angles with their axes or by changing the angular relations of the axes of the work and of the grinding wheel.

15 The drive of the spindles 3 is so arranged that the pull thereof is in the same direction as the resultant of the forces acting on the roller being ground. Thus there is no tendency for the rollers to move out of position 20 and they are ground very accurately. Likewise, the drive on the grinding wheel is disposed so as to exert a pull thereon in a more or less horizontal direction instead of a vertical direction and thus the drive does not tend 25 to lift the grinding wheel from the work and then drop it onto the work. There is a certain amount of looseness in bearings due to the existence of a film of oil that may vary in thickness and due to wear of the parts. 30 The above described drive arrangement always forces the work holding spindle and the grinding wheel in one direction against their respective bearings.

35 The grinding machine and process hereinbefore described have numerous advantages. They insure the accurate grinding of the work, giving rollers a smooth finish and making them of accurately circular section throughout their length. The machine is 40 simple and easy to operate.

45 Obviously numerous changes may be made without departing from the invention and I do not wish to be limited to the precise construction shown:

45 "What I claim is:

50 1. In a machine for grinding the bearing surface of rollers for roller bearings and the like, means for rotatably holding a roller, a grinding wheel, and means for moving said grinding wheel in a substantially tangential path with respect to the bearing surface of the roller.

55 2. In a device of the kind set forth, means for rotatably holding a conical roller for roller bearings, a pivotally mounted arm, a grinding wheel mounted at the end of said arm for grinding the bearing surface of said roller, and means for swinging said arm so

that the axis of said grinding wheel traverses the straight line passing the axis of the work 60 and the pivot of said arm.

65 3. A grinding machine for grinding the bearing surface of rollers for roller bearings, comprising means for rotatably holding a roller, a pivoted arm, a grinding wheel rotatably mounted at the end of said arm, and means for swinging said arm to raise said grinding wheel and permit it to lower to 70 grind the roller, said means permitting the grinding wheel to drop below the straight line passing through the axis of the work 75 and the pivot of said arm.

75 4. A grinding machine for grinding the bearing surface of rollers for roller bearings, comprising means for rotatably holding a roller, a pivoted arm, a grinding wheel rotatably mounted at the end of said arm, and means for raising said grinding wheel and permitting it to lower to grind the roller, 80 said means including a cam and permitting the grinding wheel to drop below the straight line passing through the axis of the work 85 and the pivot of said arm.

85 5. In a grinding machine adapted to grind the bearing surface of rollers for roller bearings, means for rotatably supporting a roller and for positively rotating the same, a grinding wheel, means for moving said grinding wheel in a path substantially tangential with respect to the bearing surface of the roller, 90 the path of movement of the axis of said grinding wheel traversing a line perpendicular to the direction of its motion and passing through the axis of the roller.

95 6. In a grinding machine, a drive mechanism for a work holding spindle, comprising a belt driven from above, a bracket secured to the frame of the machine and pulleys rotatably secured to said bracket and guiding said belt, one of said pulleys being below the level of the work spindle, whereby the pull of the belt on said spindle is downwardly, the angle being substantially the same as the resultant of other forces acting on the work.

100 7. A process for grinding the bearing surface of rollers for roller bearings and the like that comprises swinging a grinding wheel about a pivot in a path such that the axis of the grinding wheel traverses a straight line that passes through the axis of the work and the pivot about which said grinding wheel is swung.

110 Signed at Canton, Ohio, this 28th day of May, 1923.

HERBERT VANDERBEEK.
